US00D867422S

(12) **United States Design Patent** (10) **Patent No.:** **US D867,422 S**
(45) **Date of Patent:** **** Nov. 19, 2019**

(54) **CAMERA**

(71) Applicant: **TWOEYES TECH, INC.**,
Gyeonggi-Do (KR)

(72) Inventor: **Hun Joo Song**, Yongin-si (KR)

(73) Assignee: **TWOEYES TECH, INC.**, Anyang-si
(KR)

(**) Term: **15 Years**

(21) Appl. No.: **35/504,964**

(22) Filed: **Nov. 15, 2017**

(80) **Hague Agreement Data**

Int. Filing Date: **Nov. 15, 2017**

Int. Reg. No.: **DM/099373**

Int. Reg. Date: **Nov. 15, 2017**

Int. Reg. Pub. Date: **May 18, 2018**

(30) **Foreign Application Priority Data**

Aug. 17, 2017 (KR) 30-2017-0038190

(51) **LOC (12) Cl.** **16-01**

(52) **U.S. Cl.**

USPC **D16/202**
